FUEL INJECTION PUMP

Charles A. Lindeman, Jr., Chicago, Ill.

Application December 16, 1940, Serial No. 370,289

14 Claims. (Cl. 103—41)

This invention relates in general to a high pressure pump for a periodic discharge of small measured quantities of fluid, particularly in internal combustion engines. This invention relates particularly to fuel pumps of the positively actuated plunger type with a suitable by-pass controlled by a valve and having important novel objects and advantages, among which are: to provide a leakage return from the nozzle valve spring chamber which prevents pressure from building up and restricting the opening of the injection valve; to permit use of the pump and nozzle in upright or inverted position without making material changes in the structure; to provide a by-pass valve which produces a very sharp ending of injection to stop dribbling; to avoid the formation of a vacuum in the plunger chamber as fuel is allowed to enter when the plunger is retracted by the spring, and therefore no air is taken in along the plunger; in providing a pintle in the spring nozzle which prevents clearance when the valve is closed, thus squeezing out fuel and preventing carbon from forming in the nozzle; to provide means for easily testing the nozzle injection pressure; in providing an injection pump with a variable beginning and a fixed ending, a fixed beginning and a variable ending, or a variable beginning and a variable ending, without making any material changes in the pump structure; and in general to provide the structure herein shown and described.

Other objects of the invention will appear in the specification and will be apparent from the accompanying drawings in which:

Fig. 1 is a cross sectional view illustrating an injection pump mechanism in accordance with this invention;

Fig. 1A illustrates a modification of the structure of Fig. 1;

Fig. 2 is an enlarged cross sectional view taken on the line 2—2 of Fig. 1;

Fig. 3 is a sectional view taken on the line 3—3 of Fig. 2;

Fig. 4 is a sectional view taken on the line 4—4 of Fig. 1;

Fig. 5 is a sectional view taken on the line 5—5 of Fig. 2; and

Fig. 6 is a view taken on the line 6—6 of Fig. 2.

In this invention, a by-pass valve separate from the pump chamber is connected to permit by-pass of fuel from the pump chamber and is separately and adjustably operated by means of a connection with the pump operating rocker arm so that an easily accessible external control means is provided which is adjustable for controlling the beginning and ending of injection without varying the stroke of the pump.

Referring now more particularly to the drawings, a pump plunger 10 is slidably mounted in one end of a close fitting plunger barrel 11, the

other end of the barrel being threaded into a reduced bore in a pump casing 12, the bore being continued to provide a plunger compression chamber 13. A plunger spring 14 surrounds the 5 plunger and the plunger barrel and is seated at one end against a flange 15 projecting outwardly from the barrel and at the other end against flanged head 16 at the end of the plunger. The pump plunger is freely movable in a bore 17 provided in a projection 18 of the pump casing, and a plunger tappet guide 20 is threaded into the outer end thereof. A plunger tappet 21 is inserted through the guide to engage the pump plunger head 16 at its inner end and is engaged 10 at its outer end by a tappet roller 22 mounted at one end of a pump rocker arm 23. The rocker arm is pivoted intermediate its ends upon a rocker shaft 24 and has a rocker arm push rod 25 connected at the other end of the arm for reciprocating the pump plunger periodically against the action of the plunger spring 14.

Mounted in a recess in the upper end of the projection 18 is a rod 9 adjustably held by a set screw 8 and having graduations 1 disposed 20 adjacent the tappet 21 to measure and indicate the position of the pump plunger in relation to the time of opening of the by-pass valve.

Extending from the plunger chamber 13 in the pump casing 12 is a high pressure fuel passage 30 which leads to the lower end of the casing where it communicates with an annular space 21 between the pump casing and an injection valve barrel 28 having a lapped joint therewith at the end of the casing. An injection valve casing 29 is threaded on the reduced end of the casing 12 and holds the barrel 28 tightly at the lapped joint. At the outer end of the casing 29 is a reduced opening through which an injection valve seat plug 30 projects, the upper end of the valve seat having a flange 31 of the same external diameter as the injection valve barrel 28 so that when the injection valve casing 29 is threaded tightly upon the end of the casing 12, the injection valve barrel 28 and the injection valve seat plug 30 are held tightly in place against the end 40 of the pump casing 12 with the extremity of the valve seat projecting from the injection valve casing.

Opening from the end of the casing 12 is a 50 spring recess 32 for containing an injection valve spring 33. Slidably mounted in the bore of the injection valve barrel 28 is an injection spray valve 34 with an inner valve pintle 35 having a pointed extremity which fits tightly in and extends entirely through an opening 36 in the injection valve plug 30. The upper end of the pintle is threaded and has an adjustment nut 37 55 forming a pintle lock which holds it in place with respect to the valve 34 because of the en-

gagement of the lower end of the valve spring 33 with the locking nut 37.

At the lower end of the valve 34, it is seated upon a tapered seat 38 closely surrounding the pintle 35 at the top of the valve seat piece 30. Extending upwardly from the valve surface is a concave groove 39 which together with a similar opposite groove 40 at the adjacent inner and lower edge of the valve barrel 28 form an annular high compression space 41 connected to the annular space 27 at the top of the valve barrel by inclined passages 42 in the barrel.

Pressure is applied by the pump plunger 21, from chamber 13 through passage 26, space 27, passages 42 to the compression space 41. When this pressure is sufficient, injection valve 34 and its attached pintle 35 are raised against the pressure of spring 33 thereby injecting fuel through the opening 36 in the injection valve piece 30.

The pump casing 12 and the valve casing 29 as a unit, are inserted tightly in an opening 43 in a cylinder head 44 of an internal combustion engine which is of considerable thickness to provide space 45 for a water jacket at the outer end of the cylinder head and has a reduced bore or opening 46 at the bottom to receive the reduced end of the injection valve seat plug 30.

At one side of the pump plunger bore 17 and relatively at right angles thereto in the casing 12 is a high pressure bore and space 49 having a closing plug 50 at one end and a by-pass valve assembly at the other end. This assembly comprises a by-pass valve 51 with a long threaded stem, a valve seat 52 therefor threaded in the end of a guide 53 which in turn is threaded in the end of the bore 49 to hold it tightly in place. Slidably in the guide is a valve and tappet holder 54 into which the stem of the valve 51 is threaded, the extremity of the stem projecting beyond the outer end of the holder and having a lock nut 55 adjustable thereon. Adjacent the outer end of the holder is a flange 56 and at a distance from the outer end of the guide 53, is a flange 57 with a valve spring 58 disposed between the two flanges and tending to close the valve 51 on its seat 52.

At one side of the by-pass valve 51 is the high pressure chamber 49, and on the opposite side is a low pressure chamber 59, the valve controlling communication therewith. The high pressure chamber is connected to the plunger chamber 13 by a passage 49' extending from the high pressure chamber to a check valve chamber 60 at an angle thereto with a passage 61 from the bottom of the check valve chamber which extends into a passage 62, extending laterally from the plunger chamber 13.

Closing the top of the check valve chamber is a stud 63 and engaging a seat 64 at the bottom of this chamber is a valve 65 having an upwardly extending stem and a spring 66 engaging the valve surrounding the stem and bearing against the inner end of the stud at the other end of the chamber. This check valve opens at a pressure slightly higher than the pressure of a fuel transfer pump which delivers fuel from an outer source of supply to the pump and prevents a free flow of fuel when the by-pass valve is open. Also connected to the passage 61 is a transverse passage 67 communicating with a groove 68 at the outer side of the plunger barrel 11 and having one or more openings 69 through the plunger barrel preferably at or adjacent the top of the stroke of the pump plunger 10.

The low pressure chamber 59 is connected to the plunger bore 17 by openings 70 through the wall of the by-pass valve guide 53 which communicates with a surrounding groove 71 in the outer wall of the guide and thence through a transverse passage 72, closed at its outer end by a screw 73, leading directly into the pump plunger bore.

At the opposite side of the pump casing 12 is a relief or outlet passage 74 connected to the upper end of the spring recess 32 with closing stud 75 at the outer end. A transverse relief passage 76 extends in the casing 12 from the pump plunger bore 17 which intersects the passage 74 and is provided with terminal fittings 77 for a leakage return pipe 78 by which any leakage or by-passed fuel or liquid is returned to a fuel supply tank.

Leakage fuel or liquid will ordinarily fill the spring recess 32, outlet passage 74 and pump plunger bore 17 to the level of the relief passage 76.

In order to prevent such liquid from escaping along the stem of tappet 21, the inner end of the guide 20 is reduced in size at its inner end to provide a relief space around it communicating with the relief passage 76. To prevent pumping of liquid from this space by movement of the tappet, the inner edge of the guide opening 79 is beveled with openings 80 extending through the wall of the guide at the upper or inner edge of the bevel. When the inner end of the tappet 21 is engaged by the flat flanged head 16, any entrapped liquid will be driven up the beveled edge 79 and discharge out of the openings 80 instead of following along the tappet stem.

To supply fuel for the pump plunger in the plunger chamber 13, an inclined passage 81 leads downwardly from the top of the casing 12 which is counter-bored at its outer end to provide a seat for a spring 82 which presses a check valve 83 against an opening in a stud 84 at the end of a fitting 85 to which an inlet pipe 86 is connected at the outside of the casing. This check valve admits fuel to the pump upon its suction stroke but is immediately closed by its spring 82 whenever any pressure is applied by the pump plunger 10.

Thus fuel is admitted to the plunger chamber when the plunger is raised by means of its spring 14, and when the plunger is depressed by the action of rocker arm 23, the fuel is compressed below the plunger in the chamber 13 and in all of the passages connected thereto, the high pressure passage 26 and through the pressure check valve 65 to the high pressure chamber 49. When the by-pass valve 51 is closed, the pressure produced by the pump plunger 10 will be sufficient to raise the injection valve plunger 34, injecting a small quantity of fluid under high pressure through the needle valve opening 36 of the injection valve plug 30. When the by-pass valve 51 is open, a sufficiently high pressure will not be built up to open the injection valve 34 against its spring 33 and the fuel will then be delivered through the by-pass passages and the return pipe 76 to a suitable fuel supply reservoir. The closing plug 50 is supplied for convenience at the end of the high compression chamber 49 as a bleeding plug and also for conveniently applying a pressure testing unit to determine the pressure produced by the pump in the high pressure chamber and connected passages. Manipulating the pump rocker arm 23 with this plug 50 removed will bleed the unit.

To actuate the by-pass valve, a tappet 87 is threaded on the end of the holder 54 for the

by-pass valve, free from engagement with the inside locking nut 55, but having its own lock nut 87'. This tappet is engaged by a contact roller 88 at one end of a rocker arm 89 pivoted intermediate its ends upon an eccentric 90. The eccentric is secured to a shaft 91 mounted in a bearing in an upward projection 92, attached as a separate piece as shown in Fig. 1, or forming a part of and integral with the cylinder casing 12', as shown by Fig. 1A. The shaft 91 also has an arm 93 secured thereto for rotating the shaft and thus changing or adjusting the eccentric 90. For a plurality of cylinders, this shaft may be continuous and common to all of them.

At the other end of the by-pass rocker arm is a contact roller 94 adapted to engage a cam 95 which has a split adjustment portion 96 for variably mounting it upon a hub projection 97 of the rocker arm 23. Formed on the cam 95 are projections 98 and 99, adapted to be engaged by the roller 94 as the rocker arm is actuated by its push rod 25. When the roller 94 is at the outer ends of the projections, the opposite end of the by-pass rocker arm 89 pushes the tappet 87 inwardly, opening the by-pass valve 51, and when the roller rests in the space between the projections or on the other outer portions of the cam, the opposite end of the cam is moved outwardly with respect to the tappet, allowing the spring 58 to close the by-pass valve. Thus the length of the stroke remains substantially the same, although the cam engagement may be varied to change the time of fuel injection.

To make the pump inoperative, it is necessary only to keep the valve open, and this may be accomplished by a lever 100 mounted in the flange 47 on a bearing pin 101 and having an eccentric 102 moved thereby into engagement with the adjacent end of the by-pass rocker arm 89. This holds the rocker arm and the valve in its open position where it is unaffected by the cam projections. A spring 103 connected at one end to the by-pass rocker arm, and at the other end to a fixed projection 104, secured as a bent washer under the head of a bolt 48, tends to keep the end of the arm in engagement with the tappet 87, but the by-pass valve spring 58 overcomes this spring 103 for closing the valve.

In applying the combined pump and injector to the opening 43 of a combustion engine cylinder, a flange 47 projects from the pump casing 12 having an opening therethrough through which a fastening bolt 48 is inserted. At the side opposite the flange is a rounded shoulder 105 adapted to be engaged by an overlying shoulder 106 as an extension of the mounting projection 92 if it is separate from the cylinder as shown in Fig. 1. In this case, an opening 107 is provided for another bolt 48 which is inserted therethrough and into a suitable threaded opening 108 in the cylinder head. In the construction as shown by Fig. 1A, a clamping block 109 is substituted for the corresponding extension of the projection 92 in Fig. 1, and the pump and injection unit are therefore tightly held in place by the bolts at the opposite sides thereof.

In order to accurately adjust and set the projection 92 as shown in Fig. 1, the outer edge thereof may have a set screw 110 inserted through a flange in contact with the upper face of the cylinder head 44 with the lock nut 111 threaded thereon at the upper side and in contact with the upper face of the flange. By positioning the set screw as desired, the shafts 91

and 101 may be accurately located and adjusted for varying and positioning the parts mounted thereon. In attaching and applying the parts, the rounded shoulder 105 acts as a hinge for seating the extension end of the housing projection 92.

To determine the duration of injection, a socket 112 is provided at the upper end of each rocker arm 23 into which the end of a sharp instrument such as a screw driver or other suitable tool is inserted. By rocking this arm, and adjusting the by-pass valve tappet 87, the duration of injection can be accurately adjusted to coincide with other similar units of the engine.

15 The position of the tappet 21 with respect to the graduated rod 9 at the time the by-pass valve tappet roller 94 is just making contact with the cam lobes 98 and 99 thus determines the duration of injection.

20 All adjustments for the purpose of synchronizing the metering of the units should be made at the by-pass tappets 87.

25 Adjustments of the different pump and injection units should be made with the eccentric adjustment levers 93 in a fixed position for all units. If the adjustment eccentrics 90 are all mounted on a common shaft 91, they may be commonly synchronized and operated by the same lever 93 and further adjustment of the eccentric arms is thus avoided.

30 With this construction, it is possible to vary the operation of the pump in its injection of fuel at high pressure by varying the position of the cam 95 and by varying the eccentric mounting of the by-pass rocker arm. By varying this engagement with the projections of the cam, the injection pump may have a variable beginning and a fixed ending pressure, a fixed beginning and a variable ending, or a variable beginning and a variable ending without making any material changes except in this adjustment. In practice, the injection valve spring 33 has a fixed or known compression which must be overcome in order to provide for the injection of fuel at a predetermined pressure and this pressure may be determined without removing or disconnecting any part except to attach a pressure gauge in place of the plug 50 at the end of the high pressure chamber. In this type of injector, no vacuum is formed in the pump barrel or passages, thus preventing air from being taken into the pump and causing faulty injection.

35 I claim:

1. A fluid pump comprising a casing, a pump plunger movable therein, a high pressure delivery outlet for the pump, a spring pressed delivery valve for the outlet opened by high pressure fluid from the pump, a by-pass relief for the pump having a variable beginning and a variable ending and including a valve in a passage in the casing, and means for actuating the pump and operating the relief valve to control the discharge of high pressure fluid through the delivery valve.

40 2. A fluid pump according to claim 1 in which the relief passage is at an angle to the movement of the pump plunger, and said actuating means comprises a rocker arm, an adjustable double lobed cam movable with the rocker arm and a lever engaged by the cam for opening the relief valve.

45 3. A fluid pump according to claim 1 in which the relief valve is closed by a spring, the actuating means comprises a rocker arm, a cam movable with the rocker arm having high points

thereon spaced apart and alternate relatively low points, and the cam being adjustable to vary the position of the high points, and a lever engaging the cam at one end and engaging the relief valve at the other end to open the relief valve at the high points of the cam against the tension of the valve spring, the valve being closed by the spring at the said low points of the cam.

4. In a fluid pump comprising a casing, a pump plunger movable therein, a tappet projecting from the casing for moving the pump, means for actuating the tappet to operate the pump, a graduated gauge supported adjustable in the casing adjacent the projecting end of the tappet independent of the actuating means and having the graduations to indicate the length of stroke of the tappet of the pump.

5. A fluid pump comprising a casing, a pump plunger movable therein, a high pressure delivery outlet for the pump, a spring pressed delivery valve for the outlet opened by high pressure fluid from the pump, a by-pass relief for the pump including a valve in a passage in the casing connected to the high pressure side of the pump, a rocker arm for actuating the pump, a cam movable with the rocker arm having alternate high and low portions, a lever engaging the cam at one end and the relief valve at the other, a spring tending to keep the relief valve closed and the lever in contact with the cam, and an eccentric bearing intermediate the ends of the lever.

6. The combination with a pump structure according to claim 5 of a manually operable device for engaging the valve operating end of the lever and holding it and the valve inwardly against the pressure of the valve spring to prevent operation of the lever by its cam and to hold the relief valve open.

7. In a fluid pump, a pump plunger, a casing having a spring chamber for the pump plunger and a high pressure discharge chamber, a high pressure delivery outlet for the pump, a by-pass relief for the pump including a valve in a passage in the casing at one side of the pump chamber, leakage return passages in the casing connected to the pump spring chamber and to the by-pass relief passage, a tappet extending into the pump spring chamber for actuating the pump plunger, and a mounting extending into the chamber and having a bore for the tappet having relief means at the inner end thereof within the pump spring chamber, the pump plunger movable from and engaging the inner end of the mounting, the relief means preventing fluid from being discharged from the bore around the tappet by the engagement of the pump plunger with the end of the mounting.

8. In a fluid pump, the combination with a casing, a pump plunger movable therein, a high pressure delivery outlet for the pump, a by-pass relief for the pump including a valve in a passage in the casing, a rocker arm for operating the pump plunger, a cam carried by the rocker arm, a lever engaging the cam for operating the relief valve and means forming a socket at the outer side of the rocker arm for receiving a tool inserted therein for manually reciprocating the rocker arm to bleed fluid from the pump casing.

9. In a fluid pump, a casing, a pump plunger movable therein, a high pressure chamber and a high pressure delivery outlet for the pump, a spring pressed delivery valve for the outlet and

passages in the wall of the casing for high pressure fluid from the pump chamber to the delivery outlet and said valve, a by-pass relief for the pump including a valve in one passage in the casing, and a connection to said passage at one side of the relief valve from the high pressure chamber of the pump, a fluid relief passage connecting with the by-pass relief passage at the other side of the valve, means for operating the pump, and means for positively operating the relief valve at the beginning and ending of fuel injection to control the duration and discharge of high pressure fluid from the high pressure delivery outlet for the pump.

10. A structure in accordance with claim 9 in which the high pressure delivery valve has a spring chamber in the casing and a passage in the wall of the casing from the spring chamber to the relief side of the by-pass relief passage so that the entire leakage from the by-pass and from the pump casing will have a common outlet.

11. In a fluid pump, a casing, a pump plunger movable therein, a high pressure delivery outlet for the pump at one end of the casing, means for actuating the pump at the other end of the casing, an intermediate flange projecting from the casing, a by-pass relief for the pump including a valve in a passage transverse to the pump plunger in the flange of the casing, means adjustable on the pump actuating means for actuating the valve in timed relation to the pump operation, and means for engaging said flange to hold the pump in discharging position and the valve and its actuating means in fixed relation to the pump.

12. A fluid fuel pump for an internal combustion engine in accordance with claim 11 having the pump and the relief valve in a common casing in which the delivery outlet of the casing is inserted in an opening in the engine cylinder, a fastening bolt inserted through the pump flange at one side of the casing, a shouldered projection on the flange at the other side of the casing, and a fastening means including an extension to overlie and engage said shouldered projection of the casing for additionally holding it in place.

13. A fluid pump structure in accordance with claim 11 in which the by-pass relief for the pump is located in a passage in the flange transverse to the pump plunger, the stem of the valve projecting from one end of the relief passage and the other end of the passage being closed by a removable stud to which connection can be made for measuring the pressure of fluid therein and determining the operation of the pump.

14. A fluid pump comprising a casing, a pump plunger movable therein, a high pressure delivery outlet for the pump at one end of the casing, means for operating the pump plunger at the other end of the casing, a projecting flange intermediate the ends of the casing by which it is secured in place, a by-pass relief for the pump including a valve in a passage in the flange of said casing at right angles to the pump plunger, the valve having an operating stem projecting from the flange, a cam actuated by the pump operating means, a lever engaging the cam at one end and engaging the relief valve at the other end, means for adjusting the lever to control the opening operation of the valve, and an adjustable tappet at the end of the valve stem for varying its engagement with the lever.

CHARLES A. LINDEMAN, JR.
